UNITED STATES PATENT OFFICE.

GEORGE H. TAYLOR, OF NEW YORK, N. Y.

DESIGN FOR A NECKTIE.

SPECIFICATION forming part of Design No. 23,074, dated February 20, 1894.

Application filed December 27, 1893. Serial No. 494,913. Term of patent 7 years.

To all whom it may concern:

Be it known that I, GEORGE H. TAYLOR, a citizen of the United States, residing in the city, county, and State of New York, have invented and produced a new and original Design for Neckties, of which the following is a specification, reference being had to the accompanying drawings.

Figure 1 is a view in perspective of a piece 10 of fabric embodying my design for neck-ties. Fig. 2 is a transverse section through the same, these views being deemed necessary to fully illustrate my design.

The essential feature of my design consists 15 in a neck-tie having longitudinal corrugations therein extending nearly to the ends thereof,

the ends however being left plain or uncorrugated as illustrated.

In the drawings A designates a tie embodying my design, and *aa* the corrugations formed 20 therein which terminate at *bb* near the ends B of the tie which are left plain or uncorrugated as shown.

Having described my invention, what I claim is—

The design for a neck-tie, as herein shown and described.

GEORGE H. TAYLOR.
